(57) **CLAIM**

The ornamental design for a trail camera tree mount, substantially as shown and described.

DESCRIPTION

FIG. 1 is a top plan view of the trail camera tree mount showing the new design;

FIG. 2 is a bottom plan view thereof;

FIG. 3 is a rear elevation view thereof;

FIG. 4 is a front elevation view thereof;

FIG. 5 is a top, front perspective view thereof;

FIG. 6 is a bottom, rear perspective view thereof; and,

FIG. 7 is an exemplary perspective view thereof.

The broken lines shown in the drawings depict environmental subject matter and form no part of the claimed design.
